UNITED STATES PATENT OFFICE.

ERNST GLANTZBERG, OF NEW YORK, N. Y.

COOLING AND VENTILATING SYSTEM.

Application filed April 5, 1921. Serial No. 458,861.

To all whom it may concern:

Be it known that I, ERNST GLANTZBERG, a citizen of the United States, and resident of the city of New York, borough of Manhattan, in the county of New York and State of New York, have invented a new and Improved Cooling and Ventilating System, of which the following is a full, clear, and exact description.

10 It is well appreciated in connection with the ventilation and cooling of auditoriums, and with relatively large rooms such as theatres, etc., that it has been quite customary to provide ventilators which have served 15 to draw off the heated air at a point in the ceiling or adjacent same, and further means has usually been provided for forcing fresh air into the space to be ventilated.

These devices and systems have for the 20 most part, proven far from satisfactory, in that pockets of stale air have been formed which have not been affected to a material extent by the ventilation provided. This is to be attributed to the fact that air, lacking 25 in oxygen, is not necessarily warm, and consequently the same will fail to rise to a point at which it may be drawn off by the discharge ventilator, or means provided for this purpose.

30 Also, fresh air, where introduced at a point near the floor of the room, would fail to permeate the atmosphere of the room, and thus pockets of air relatively rich in oxygen, would be formed, which pockets in 35 many instances would fail to reach the respiratory organs of most of the persons within the room.

A further difficulty experienced, has been 40 that the air introduced into the space to be ventilated has often flown in a jet or stream, so that persons in the direct path of this blast have experienced disagreeable effects endangering health.

Also the air introduced into the space to 45 be ventilated has, in most instances been extremely dry so that the air becomes what might be known as "starved for moisture" again resulting detrimentally to health.

Aside from these objections, air introduced 50 under present systems has not acted as a stimulating agent for the reason that the same, in most instances has been more

highly heated than the atmosphere of the space into which it was introduced, particularly during the summer months, and in 55 this connection it will be noted that air of a higher temperature than the atmosphere of the space to be ventilated would necessarily rise immediately to the highest point, thus further complicating the difficulties of proper 60 distribution of the fresh air, as has been brought out in the preceding paragraphs.

Thus the major defects of ventilating systems at the present time are five fold; first, that the fresh air has been improperly introduced, so that pockets of stale air have been 65 permitted to come into being, without being dissipated by the ventilating system to any appreciable extent; second, the stale air has not been properly removed from the space 70 into which the fresh air was being introduced; third, that the fresh air has been introduced in the form of a jet or blast to the detriment of persons in the direct path of said jet; fourth, that the moisture content of 75 the air was in many instances insufficient, and fifth, that the fresh air has been improperly cooled.

With this in mind, I have provided a ventilating system, more particularly adapted 80 for the ventilation of relatively large enclosed spaces, such as churches, auditoriums, theatres, etc. and by means of which the fresh air will be introduced in such a manner that the same will permeate all of the 85 atmosphere of the space so that an even volume of air fit for human consumption is present, at all times, within the space, thus avoiding the present defect in which stratas of fresh, cold air, and stale air are to be 90 found in pockets beside and above each other.

A further object of my invention is the provision of a system of the nature specified, together with apparatus permitting of 95 its operation, which will force the proper removal and escape of the stale air.

A still further object of my invention is the provision of certain means which will effectually preclude the forming of any jet or direct blast of air which would detrimentally affect the occupants of the space.

Another object of my invention is the provision of a system permitting of ventilation

being effected, which system will insure the provision of an ample moisture content to the atmosphere of the space to be ventilated.

Still another object of my invention is the provision of a system of the type specified which will adequately cool the fresh air introduced, so that the same serves as a stimulant to the occupants of the space to be ventilated.

19 Further objects of my invention will appear in the annexed specification and drawings which latter present practical embodiments of my invention, and in which—

15 Figure 1 is a somewhat diagrammatic sectional view taken through one of my ventilating units.

Figure 2 is a horizontal sectional view on line 2—2 of Figure 1.

20 Figure 3 is a vertical sectional view taken along the lines 3—3 in the direction of the arrows indicated in Figure 1.

Figures 4 and 5 illustrate details of construction which may be utilized to advantage in some instances.

25 Figure 6 is a horizontal sectional view of an auditorium such as that of a motion picture theatre, and showing the system of distribution accomplished by the utilization of a single unit such as has been illustrated 90 in Figures 1, 2 and 3, the section being on the line 6—6 of Figure 7.

Figure 7 is a longitudinal sectional view taken along the lines 7—7 of Figure 6, and

35 Figure 8 illustrates my invention as applied to an auditorium similar to that illustrated in Figures 6 and 7, but showing the system of current flow produced upon the utilization of a pair of units constructed 100 in accordance with my invention, and the distribution of air effected thereby.

40 Referring now more particularly to Figures 1, 2 and 3, it will be seen that in the embodiment illustrated, I primarily provide a housing, which preferably includes the roof 10, and outer walls 11. This housing is subdivided into four major compartments, 12, 13, 14 and 15, respectively, which are provided by utilizing vertically extending 110 walls 16, a horizontal partition 17 and discharge passages 18.

45 It will be noted that the outer walls 11 are provided with openings 19 at points preferably adjacent the roof 10, and above the horizontal partition 17, which latter extends at this point in an inclined plane, so as to provide what might be termed a gutter 20 for a purpose hereinafter more fully specified.

50 The walls 16 are formed with upper openings 21, affording communication between the compartments 12 and 13, and below the horizontal partition 17, the walls 16 are formed with outer openings 22 providing a passage between the compartments 13 and

14, the discharge tubes or compartments 15 opening directly, as has been indicated in Figure 1, into the compartment 14. Thus a flow of fluid is permitted from the outer atmosphere into the space with which the compartments 15 communicate at their lower end.

55 Now with a view of providing means serving to effect a flow of current in this manner, it will be noted that I utilize any suitable type of driving motor 23, which latter serves to effect a rotation of a shaft 24 associated with blower fans 25 arranged in line with each of the openings 22. Thus upon an actuation of the motor, air will be 80 sucked through the opening 19 into the compartment 12, and so into the compartment 13, whence it will be discharged through the tubes or compartments 15 after passing through the compartment 14. 85

90 In the embodiment illustrated, it will be seen that the housing includes a pair of diametrically opposite intake openings 19, as well as a duplicate set of compartments, but it is to be appreciated that the housing may embrace any suitable number of compartments, and associated elements, the contour of this housing being susceptible to variation according to the structure which it embraces. Also a belt 26 extends between 95 the motor 23 and the shaft 24, and with a view to provide means which will permit of any stretching of this belt to be compensated for, I preferably utilize a structure capable of operation by an unskilled person, thus avoiding expense incident to 100 operation.

105 This structure preferably embraces a plurality of screw threaded studs 27 clearly indicated in Figure 4, which studs extend through openings in the base 28 of the motor 23, and serve to retain this base from any movement by virtue of a retaining element such as a nut 29, engaging with slotted washers 30, one of which is shown in perspective in Figure 5. Thus it will be but the work of an instant for an unskilled operator to manipulate the parts aforescribed to effect a movement of the motor 23 in a plane which will result in a taking up of all slack 115 on the part of the belt 26, and thus preventing any slipping on the part of this element.

110 Assuming now that the discharge compartment or tubes 15 are in communication with space to be ventilated, it will be seen 120 that jets of air will emerge therefrom, thus presenting the same difficulty as has been brought out in the preamble, and with a view of overcoming this difficulty, or in other words to break these streams or jets 125 of air into minute puffs, I utilize valves, which in the embodiment illustrated are in the nature of paddles 31, mounted upon a rotatable shaft 32, extending transversely of the housing, and being conveniently 130

driven by any suitable means such as a belt 33 upon a rotation of the shaft 24. Also these valves, as will be noted, co-operate directly with the compartments 15, and it 5 will be seen, assuming that a pair of these latter compartments are provided for each of the compartments 14, that by arranging these paddles at right angles with respect to each other, that the jets discharged from 10 the tubes or compartments 15 will come into being at different intervals. In other words, the compartments 15 will discharge air current alternately, one of the same preventing the passage of any air when the second is 15 fully opened.

Thus means are provided, which will prevent the discharge of a steady stream or jet into the space to be ventilated, so that the 20 objections incident to this phase of ventilating systems are avoided.

To now provide means which will serve to effectually cool air passing through the housing, I preferably utilize conduits 34 in communication with coils 35, which conduits 25 serve to introduce brine or ammonia into the coils 35, and to circulate the same through these coils, the fluid having been previously treated to reduce the temperature of the same, so that the coils will act in the 30 nature of radiators to cool all air passing through the compartment 12.

Thus a medium is provided accomplishing the purpose desired, where the exterior temperature is higher or equally as high as 35 the temperature of the space to be ventilated, but it will be perfectly obvious that should it be desired to employ my ventilating system in the nature of a heater, as well as for the purpose of ventilation, that 40 the heated fluid may be circulated through the coils 35 to produce the opposite result.

Now with a view of humidifying the air, as well as causing a deposition of those particles within the same, I conveniently utilize 45 a transversely extending spray pipe 36, which may communicate through a pipe 37 with a source of fluid supply (not shown). Thus upon the air flowing in the manner aforescribed, through the housing, it will 50 be subjected to a humidifying, cleansing and cooling action, and it is to be noted that the water particles not introduced in a state of suspension into the air will flow into the trough 20 from whence it may be 55 drawn through an outlet pipe 38.

In the event that the occurrence described in the preceding paragraph is too long in operation for any length of time, in which event it would be desirable to guard against 60 the entrance of elements into the same, I may conveniently provide doors 39 for effecting this purpose, which doors are hingedly secured to the under side of the roof 10, as at 40, which are normally retained in a position at which they will act

as deflectors for guiding the air into the compartment 13 by means of suitable catches 41. Upon a release of these catches however, the doors 39 will fall to a position at which they will effectually cover the 70 openings 21, and obviously prevent any flow of fluid into the compartment 13.

Referring now more particularly to Figures 6 and 7, which illustrate a motion picture theatre, including a screen 42, roof 43, balcony 44 and ground floor 45, these latter spaces are provided with the conventional outlet doors 46, and it will be seen that the ventilator housing is preferably positioned at a remote point from these doors, and is 80 mounted upon the roof of the theatre. Also the compartments 15 or discharge tubes, extend through openings in the roof 43, and further guard against the entrance of dust particles may be provided by a suitable screening 47 associated with the lower end 85 of each of the compartments 15.

It will be noted, in the figures referred to, that the air will be drawn through the housing in the manner aforespecified, and 90 will flow through the space extending between the balcony and roof, and the ground floor and balcony respectively, and discharge through the openings or doors 46.

In the event that the theatre is a relatively 95 large one, it may be found desirable to mount a second housing upon the roof 43, and with this in view, reference is had to Figure 8 in which it will be noted that a second ventilator is positioned adjacent the rear end of the balcony, the air introduced into the space by this ventilator flowing down the incline of the balcony and cascading over the front edge thereof to the ground floor, thus providing a double source 100 of ventilation, at the most constricted point of the theatre, to wit, that portion of the orchestra below the balcony.

Also the second ventilator will produce 110 air currents serving to rebuff any tendency on the part of the air currents produced by the ventilator at the innermost end of the theatre to rise to the balcony as is the case in Figures 6 and 7, and the foul air be discharged through the exit doors or other 115 openings provided for this purpose at the rear of the ground floor.

Thus it will be seen that I have provided a ventilating system, which is primarily intended for the introduction of cool fresh air 120 into an auditorium, or other space to be ventilated, which air will be introduced at the highest point, and thus, incident to the well known law of physics will fall through the heated layers, and to the points to be ventilated, at the same time permeating and breaking up these heated stale layers of air and disposition of the same.

Also the air introduced will not be in 130 the nature of steady streams or jets, which

will act as drafts and endanger the health of the occupants of the space being ventilated by virtue of the fact that the air will be introduced in relatively minute puffs effectively preventing this occurrence.

Further, the air will be thoroughly cooled, cleansed and humidified so that independent of drafts, a thoroughly healthy medium will be introduced into any space desired, and brought to a point at which it will thoroughly and effectually permeate the heated air pockets. It will obviously be appreciated that the illustrations resorted to are merely in the form of particular embodiments, and it will be readily appreciated that any number of diversions might be resorted to without in the least departing from the scope of my claims, which are—

1. A ventilator, comprising a housing having an air inlet in its upper part and two discharge openings in its bottom, means for drawing air into the housing, and means for controlling the discharge openings, whereby the air will be continuously discharged in alternate streams through said discharge openings.

2. A ventilator, comprising a housing having two communicating compartments, one of the compartments having an air inlet opening and the other two discharge openings, a means for drawing air into the compartment having the inlet opening, and forcing it into the compartment having the discharge openings, and means for controlling the discharge openings, whereby the air will be alternately discharged through said openings.

3. A ventilator, comprising a housing having two communicating compartments, one having an air inlet and the other two discharge openings, a fan for drawing air into the compartment having inlet opening and forcing it into the compartment having the discharge openings, a valve controlling each discharge opening, and means for operating said valves, whereby the said openings will be alternately closed and opened.

4. A ventilator comprising a housing having two communicating compartments, one having an air inlet and the other two discharge openings, means for drawing air into the compartment having inlet opening and

forcing it into the compartment having the discharge opening, a valve controlling each discharge opening, each valve comprising paddles, the paddles of one valve being at right angles to the paddles of the other valve, and means for operating the valves, whereby the discharge openings will be alternately opened and closed.

5. A ventilator, including a housing, vertical and horizontal walls, dividing said housing into a plurality of compartments, said housing being formed with intake openings communicating with certain of said compartments, the walls of said last named compartments being in turn formed with openings providing communication into a common compartment, discharge tubes, certain of said vertical walls being formed with further openings affording communication between said last named compartment and discharge tubes, and means within said last named openings for drawing air into said intake openings, and discharging the same through said discharge tubes.

6. A ventilator, including a housing, vertical walls within said housing, a horizontal partition arranged between the roof and lower edge of said housing, said vertically extending walls being formed with openings above and below said partition, fans arranged in certain of said openings for producing a current of air through said housing, discharge tubes arranged in the lower end of said housing, valves co-operating with said discharge tubes, and means for driving said fans and valves.

7. A ventilator, including a housing, vertical walls within said housing, a horizontal partition arranged between the roof and lower edge of said housing, said vertically extending walls being formed with openings above and below said partition, fans arranged in certain of said openings for producing a current of air through said housing, discharge tubes arranged in the lower end of said housing, a rotatable shaft at the upper ends of the discharge tubes, valves secured to said shaft and extending into said discharge tubes, and means for rotating said fans and shaft.

ERNST GLANTZBERG.
